US00D945918S

(12) United States Design Patent (10) Patent No.: US D945,918 S
(45) Date of Patent: * Mar. 15, 2022

(54) ARTICLE OF JEWELRY

(71) Applicant: RICHEMONT INTERNATIONAL SA, Villars-sur-Glane (CH)

(72) Inventor: Christopher Lopez, Bernex (CH)

(73) Assignee: RICHEMONT INTERNATIONAL SA, Villars-Sur-Glane (CH)

() Term: 15 Years

(21) Appl. No.: 29/733,519

(22) Filed: May 4, 2020

(30) Foreign Application Priority Data

Mar. 27, 2020 (WO) WIPO93644

(51) LOC (13) Cl. 11-01

(52) U.S. Cl. D11/84
USPC .....
